PAGE 2

Fig. 1 is a front perspective view of an ice cream freezer showing our new design, the rear being substantially plain as indicated in Figs. 3, 4 and 5;

Fig. 2 is a front elevation thereof;

Fig. 3 is a top plan view of the freezer; and

Figs. 4 and 5 are side elevational views taken from the right and left, respectively, of Fig. 2.

The essential features of our design reside in the full-line portions in the drawings.

We claim:

The ornamental design for an ice cream freezer, as shown and described.
